(57) **CLAIM**

The ornamental design for an instrument panel for media and navigation systems, as shown and described

DESCRIPTION

FIG. 1 is a front view of an instrument panel for media and navigation systems, showing our new design; and,

FIG. 2 is a front, left side perspective view thereof, the right side perspective being a mirror image.

All sides not shown in the application form no part of the claimed design.

The broken line portions of FIGS. 1 and 2 are included to show unclaimed subject matter only and form no part of the claimed design.

1 Claim, 1 Drawing Sheet

FIG. 1

FIG. 2
